UNITED STATES PATENT OFFICE.

JAMES WILLIAM CARTER, OF ABILENE, TEXAS.

ELECTRIC-LIGHT HANGER.

No. 834,449.

Specification of Letters Patent.

Patented Oct. 30, 1906.

Application filed May 11, 1906. Serial No. 316,375.

To all whom it may concern:

Be it known that I, JAMES WILLIAM CARTER, a citizen of the United States, residing at Abilene, in the county of Taylor and State of Texas, have invented a new and useful Electric-Light Hanger, of which the following is a specification.

This invention relates to hangers for incandescent lamps, and has for its object to provide a comparatively simple inexpensive hanger designed for attachment to a ceiling or other suitable support and by means of which the lamp may be conveniently raised or lowered and supported at any desired height.

A further object of the invention is to provide a hanger having a roller journaled therein for engagement with the flexible lamp-supporting conductor, said roller being free to revolve in one direction and locked against rotation in the opposite direction.

A further object is to provide a weight adapted to engage the flexible conductor and forming a counterbalance for the lamp, and means whereby the conductor may be readily placed in position on or detached from the hanger.

A still further object is to generally improve this class of devices so as to add to the utility, durability, and efficiency, as well as to reduce the cost of manufacture.

With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a part of this specification, Figure 1 is a side elevation of a hanger constructed in accordance with my invention. Fig. 2 is an end view of the hanger detached. Fig. 3 is a perspective view of the hanger, roller, latch, and locking member detached. Fig. 4 is a side elevation illustrating a modified form of the invention.

Similar numerals of reference indicate corresponding parts in all of the figures of the drawings.

The improved device consists of a supporting bracket or hanger 5, provided with terminal angularly-disposed arms 6 and 7, one of which is formed with a threaded ex-

tension 8 for attachment to a ceiling or other suitable support 9, as shown. Extending laterally from the bracket or hanger 5 is a pin or stub-shaft 10, upon which is journaled a pulley or roller 11, having one side thereof formed with a plurality of recesses or notches 12, adapted to receive the pin 13 of a spring-locking member 14. The walls of the notches 12 are inclined or beveled toward the shoulders 12', while the free end of the pin 13 is correspondingly beveled, so that when the roller is turned in one direction the inclined face of the pin 13 will ride over the inclined walls of the notches without effecting the roller, and when the latter is turned in the opposite direction the pin will bear against the shoulders 12', and thus lock the roller against further movement. Pivoted to the arm 6 is a swinging latch 15, the free end of which is provided with a slot or recess 16, adapted to receive a screw or similar locking device 17, threaded in an opening in the lower arm 7. The locking member 14 and latch 15 are retained in position on the arm 6 by means of a screw or pin 18, said latch being formed with an opening or aperture to permit the passage of the locking-pin 13.

Secured to a ceiling-block or rosette 19 is one end of a flexible conductor 20, the opposite end of which passes over the roller 11 and terminates in a lamp 21. Engaging the conductor 20 is a roller 22, provided with a depending weight 23, which forms a counterbalance for the lamp 21, so that the latter may be conveniently raised or lowered and supported at any desired height. The roller 11 is free to revolve in one direction when the lamp is lowered, but is locked against rotation in the opposite direction so as to prevent the weight from having a tendency to elevate the lamp, the friction between the rope and the grooved face of the roller serving to retard the upward movement of the lamp. The latch 15 is free to swing laterally to open position, so as to expose the notched or recessed side of the roller 11, and thereby permit the flexible conductor to be readily placed in position upon or removed from said roller without the necessity of detaching the lamp.

Attention is called to the fact that the screw 18 forms a pivotal connection for both the latch and locking member, while the screw 17 by engagement with the adjacent end of the latch serves to lock the same in closed or operative position.

In operation when it is desired to attach or detach the conductor the clamping-screw 17 is released, after which the pin 13 is disengaged from the notches 12 by exerting a lateral pull on the terminal handle 24 of the locking member and swinging said member and latch laterally to open position. The conductor is then passed over the roller and the latch, together with the locking member, 10 swung downwardly into engagement with the screw 17, which latter is subsequently tightened, so as to firmly lock the parts.

In some cases a check-cord 23' is attached to the ceiling with its opposite end secured to the bracket of the pulley 22, so as to limit the downward movement of the take-up weight.

In Fig. 4 of the drawings there is illustrated a modified form of the device in which a plurality of hangers or brackets 5' are disposed at spaced intervals on the ceiling or other suitable support, and the flexible conductor 20' threaded through the rollers to form a series of depending loops 25, each loop being provided with a counterweight 26. 20 This form of the device is principally designed for supporting lamps in which the flexible conductor is of considerable length, the weights 26 being preferably formed of rubber, so that the combined weight of the 25 same will not overbalance the weight of the lamp.

From the foregoing description it will be seen that there is provided an extremely simple and inexpensive device admirably adapted for the attainment of the ends in view.

Having thus described the invention, what is claimed is—

1. A hanger provided with means for attachment to a support and having a pin extending laterally from one side thereof, a roller journaled on the pin, a latch bearing against the pin for preventing accidental displacement of the roller, a flexible lamp-supporting conductor engaging the roller, and a weight carried by the conductor and forming a counterbalance for the lamp.

2. A hanger provided with means for attachment to a support, a roller journaled in the hanger and having notches formed in one side thereof, a spring-locking member carried by the hanger and adapted to engage said notches for locking the roller against rotation in one direction, a flexible lamp-supporting conductor engaging the roller, and a weight carried by the conductor and forming a counterbalance for the lamp.

3. A hanger provided with means for attachment to a support, a roller journaled in the hanger and having one side thereof

formed with a plurality of notches, a latch engaging the roller and movable laterally to inoperative position, a locking member carried by the latch and passing through an opening in the latter for engagement with the notches, 65 and a flexible lamp-supporting conductor carried by the roller.

4. A hanger comprising a bracket provided with angularly-disposed arms one of which is formed with an extension for attachment to a support, a pin extending laterally from the hanger, a roller journaled on the pin and having notches formed in one side thereof, a latch pivoted to the hanger and engaging the pin, a locking member carried by the 70 latch and provided with a lug passing through an opening in the latch for engagement with the notches, a flexible lamp-supporting conductor engaging the roller, and a weight carried by the conductor and forming 75 a counterbalance for the lamp.

5. A hanger comprising a bracket provided with angularly-disposed arms and an intermediate laterally-extending pin, a roller journaled on the pin and having a plurality 85 of notches formed in one side thereof, a latch pivotally mounted for swinging movement on the hanger and forming a closure for one end of the same, a spring-catch carried by the latch and provided with a locking-pin passing through an opening in the latch for engagement with the notches, means for locking the latch in closed position, a flexible lamp-supporting conductor suspended from the roller, and a weight carried by the conductor and forming 90 a counterbalance for the lamp.

6. A hanger comprising a bracket provided with angularly-disposed arms and an intermediate pin, a roller journaled on the pin 100 and having a plurality of notches formed in one side thereof, a latch pivoted to one of the arms and forming a closure for one side of the hanger, said latch being provided at its free end with an inwardly-extending slot, a 105 spring-locking member carried by the latch and having a locking-pin passing through an opening in the latch for engagement with the notches, a clamping-screw carried by the opposite arm and engaging the walls of the slot 110 for locking the latch in operative position, and a flexible lamp-supporting conductor engaging the roller.

In testimony that I claim the foregoing as my own I have hereto affixed my signature 115 in the presence of two witnesses.

JAMES WILLIAM CARTER.
